UNITED STATES PATENT OFFICE.

WILLIAM DALTON, OF SCHENECTADY, NEW YORK.

STEAM-BOILER SUPERHEATER.

997,440.

Specification of Letters Patent. Patented July 11, 1911.

Application filed January 13, 1911. Serial No. 692,445.

To all whom it may concern:

Be it known that I, WILLIAM DALTON, of Schenectady, in the county of Schenectady and State of New York, have invented a 5 certain new and useful Improvement in Steam-Boiler Superheaters, of which improvement the following is a specification.

My invention more particularly relates to steam boiler superheaters of the fire tube 10 type, and its object is to provide means for connecting the pipes within which the steam is superheated, with the saturated steam supply and superheated steam delivery pipes, which shall be simple and inexpensive 15 structurally, readily applicable in connection with other elements of superheaters of different classes, and exempt from the structural and operative objections which have been developed in headers of various constructions heretofore essayed in practical 20 service.

The improvement claimed is hereinafter fully set forth.

In the accompanying drawings: Figure 1 25 is a vertical longitudinal central section through the forward portion of a locomotive boiler, illustrating an embodiment of my invention; Fig. 2, a horizontal section through the same, the upper half showing 30 the members therein in plan, and the lower half being in section, on the line *a a* of Fig. 1; Fig. 3, a vertical transverse section, on the line *b b* of Fig. 1, with the stack removed; Fig. 4, a half vertical transverse section, on an enlarged scale, through the connection casing, on the line *c c* of Fig. 2; Fig. 5, a similar section, showing a structural modification; Fig. 6 a partial vertical transverse section, on the same scale, 35 through the connection casing and T head, on the line *d d* of Fig. 2; Fig. 7, a similar section, illustrating a structural modification; Fig. 8, a partial transverse section, on a further enlarged scale, through the connection casing, showing a modification of 40 the manner of securing the sections thereof one to the other and to the diaphragm; Fig. 9, a similar section, showing the application of a non-conducting plate to the diaphragm; Fig. 10, a partial horizontal section through 45 the connection casing, on the line *e e* of Fig. 9; Fig. 11, a plan view of a collet or joint ring for seating a superheating pipe in a yoke; Fig. 12, a view, in elevation, of half 50 of a collet, in position in a yoke; and Fig. 13, an enlarged sectional view, showing the

connection between the superheater tubes and the casing.

My invention is herein exemplified in connection with a locomotive boiler, 4, having a plurality of fire tubes, 4^a, extending, in the usual manner, from a firebox at its rear end (which is not shown) to a smoke box, 4^a, connected to its front end, and supported on cylinder saddles, 12. The products of combustion passing from the tubes to the smoke box are discharged therefrom through a stack, 4^b, having an inward extension or penetration, 4^{ba}. Steam is supplied from the boiler through a main steam pipe or dry pipe, 61, and T head or breeching pipe, 62, to branch steam pipes, 63, leading to the cylinders, after passing through a superheater, comprising a plurality of loops or return bends of superheater pipes, 69, which are, in the instance shown, located in superheating tubes, 67, of larger diameter than the majority of the boiler tubes and extending, in the usual manner, through the upper portion of the boiler, from the firebox flue sheet to the front flue sheet.

In superheaters as known and constructed prior to my invention, the pipes which supply saturated steam from the boiler, are ordinarily, if not invariably, connected to 85 those which deliver superheated steam to the cylinders, through the intermediation of so-called "headers," which are cast metal members, of various forms and locations, transmitting steam from the supply pipes to the 90 superheater pipes and from the superheater pipes to the delivery steam pipes.

Much difficulty has been, and is now being experienced in practice with headers of 95 present constructions, due partly to their comparatively large size and weight and the difficulty of making and maintaining steam tight joints with them, and partly to the fact that it is difficult to obtain iron or steel castings which will effectively sustain the 100 strains to which they are subjected in service. My invention is designed to overcome this difficulty by the application of a connecting element of such material and structure as will exempt it, as far as practicable, 105 from the objectionable action exerted upon headers of the ordinary forms.

In the practice of my invention, I provide for the performance of the functions of the headers of prior superheaters, a connection casing, 70, which is a shell or box, composed of wrought plate metal, as steel or iron, of

the character of ordinary boiler plate, and is of substantially rectangular section and formed in two connected shell plates. The connection casing is divided, by a diaphragm or partition, 70^a, into a saturated steam chamber and a superheated steam chamber, the former being connected, as presently to be described, to forks or branches at the front and sides of the T head or breeching pipe, 62, and the latter to the branch steam or delivery pipes, 63.

As shown in Figs. 1, 3, 4, and 9, each of the shell plates of the connection casing is dished or pressed into channel form in section, and is flanged outwardly on its periphery, and the two plates are secured tightly together, on opposite sides of the interposed diaphragm, 70^a, by riveting or welding.

In the form shown in Fig. 5, only one of the shell plates is dished or bent into channel form in section and flanged, and the diaphragm is also dished or peripherally flanged and riveted or welded to it, after which it is similarly secured to the other shell plate which is flat throughout.

Fig. 8 shows the shell plates and diaphragm as united by welding, each of the shell plates being dished or pressed into channel form in section, but none of the plates being peripherally flanged.

The contour of the connection casing is dependent upon its location relatively to the breeching pipe, 62, and stack penetration, 4^{bb}; being of such form as to permit the casing to be properly connected to the former and to afford suitable clearance from the latter. In the instance exemplified, in which the connection casing is located horizontally and above the tubes, its rear and side walls are straight, and its front wall is centrally recessed sufficiently to permit its peripheral flanges to clear the stack penetration, 4^{bb}. It will, however, be obvious that my invention is applicable, without variation of structural or operative principle, in superheaters of the type in which the supply and delivery steam pipes and superheating pipes are connected to substantially vertical headers, located adjacent to the sides of the smoke box, as in Letters Patent of the United States No. 875,895, granted and issued to F. J. Cole, under date of January 7, 1908. In such case, the connection casing would be changed in contour only, as required by its difference of position, relatively to the breeching pipe and branch steam pipes, and the consequent different location of its connections with said members, but would conform in all essential structural particulars with that which is specifically herein shown and described.

The flat upper and lower walls of the connection casing are braced to resist the internal steam pressure acting thereon, by screw stays, 70^b, tapped into the shell and dia-

phragm sheets and riveted over on the outer sides of the shell sheets, and by thimbles, 70^c, expanded into the shell and diaphragm sheets, or screwed thereinto if preferred, and beaded over on said sheets, through which thimbles there are passed bolts, 72, by which the superheater pipes, 69, are secured to the connection casing, as presently to be described. The diaphragm, 70^a, is further stayed to one of the shell sheets by shorter thimbles, 70^c, through which one of the chambers of the connection casing communicates with one end of each of the lines of superheater pipes. The forks or branches of the breeching pipe, 62, and the branch steam pipes, 63, are secured to the opposite sides of the connection casing, opposite corresponding openings in the chambers thereof by bolts, 62^a, passing through thimbles, 70^c, expanded or screwed into the shell and diaphragm sheets, and having nuts, 62^b, on their ends, ball joint rings, 62^c, being interposed between the breeching pipe forks and branch steam pipes and the connection casing. The thimble, 70^c, which passes through the steam passage of each of the breeching pipe forks, may be either expanded or screwed thereinto, as indicated in Fig. 6, or be cast integral therewith, as in Fig. 7. If preferred, the thimbles, 70^c, may be dispensed with, and the bolts, 62^a, be screwed directly into the shell and diaphragm sheets, as shown in Fig. 7.

In order to prevent deflection of the diaphragm, 70^a, by the impact of the saturated steam entering the chamber above it, it may be provided with a reinforcing plate, 70^d, on one or both of its sides, said plate or plates being secured in position by the bolts, 62^a, as shown in Fig. 7, and to prevent the transmission of heat through the diaphragm from the superheated to the saturated steam, the diaphragm may be formed in two separate sheets, with an interposed sheet or layer of suitable non-conducting material, 70^e, as shown in Fig. 9.

The opposite ends of the lines of superheater pipes, 69, are secured to the connection casing by means of yokes, 71, which, as shown in Figs. 4 and 9, are drawn to a tight bearing on collars on the pipes and on the opposite shell plate of the connection casing, by bolts, 72, passing through the thimbles, 70^c, before described, and provided with nuts, 72^a. As shown in Fig. 9, the superheater pipes fit, with considerable freedom, in openings of greater diameter in the yokes, 71, to allow for lengthwise adjustment of said pipes for accurate accommodation to the seats or joints on the casing. Spherical faced washers, 72^b, are interposed between the nuts and yokes at one end, and between the nuts and thimbles at the other. As shown in Fig. 5, the thimbles, 70^c, are dispensed with, and the bolts, 72, are

screwed into the shell and diaphragm sheets. One end of each line of superheater pipes communicates directly with one of the chambers of the connection casing, and the other end of each line communicates, through one of the shorter thimbles, 70, with the other chamber of the casing. The ends of the pipe sections are spherical faced, and fit, by suitable ground joints, in corresponding seats in the adjoining shell plate of the connection casing. In order to enable the yokes to be readily removed from the tubes when required, spherically cupped collets, 73, divided into two diametric sections, are interposed between the tubes and yokes. The spherical faced end collars, 69, of the superheater pipes, 69, are made slightly smaller than the holes through the yokes, so that when the half sections of the collets are taken out of the depressions in the yokes, the latter can be slipped off the pipes.

Inasmuch as the form of the connection casing, and its position relatively to other members of a superheating appliance in which it is applied, may be varied in sundry particulars, in accordance with the conditions of application, in the discretion of a constructor skilled in the art, without departing from the spirit and operative principle of my invention, I do not limit my claims thereto to the specific embodiment herein described and shown, but include therein all structural modifications thereof which embody the essential and characteristic features of my invention.

I claim as my invention and desire to secure by Letters Patent.

1. In a steam boiler superheater connection casing, the combination of two plate metal casing sheets, one at least of which is dished or pressed into channel form in transverse section, and an intermediate diaphragm sheet, said casing and diaphragm sheets being secured together on their edges, transverse stays extending through and secured to said sheets, and thimbles extending through, terminating at, and being secured to one of the casing sheets and the diaphragm sheet, respectively.

2. In a steam boiler superheater connection casing, the combination of two plate metal casing sheets, having, respectively, a steam inlet and a steam outlet opening, and an intermediate diaphragm sheet, said sheets being secured together peripherally, thimbles fixed in the diaphragm sheet and one of the casing sheets, stay bolts fixed in the casing sheets and diaphragm sheet, superheater pipes communicating with the casing sheet ends of the thimbles, and ball joints interposed between the superheater pipes and thimbles.

3. In a steam boiler superheater connection casing, the combination of two plate

metal casing sheets, having, respectively, a steam inlet and a steam outlet opening, and an intermediate diaphragm sheet, said sheets being secured together peripherally, thimbles fixed in the diaphragm sheet and 70 one of the casing sheets, and thimbles fixed in the casing sheets and diaphragm sheet.

4. In a steam boiler superheater connection casing, the combination of two plate metal casing sheets, having respectively, a 75 steam inlet and a steam outlet opening, and an intermediate diaphragm sheet, said sheets being secured together peripherally, and a reinforcing plate secured to the diaphragm sheet opposite the steam inlet open- 80 ing.

5. In a steam boiler superheater connection casing, the combination of two plate metal casing sheets, having, respectively, a steam inlet and a steam outlet opening, and 85 an intermediate diaphragm sheet, said sheets being secured together peripherally, and a plate or layer of non-conducting material secured to the diaphragm sheet.

6. In a steam boiler superheater, the combination, with a connection casing comprising two plate metal casing sheets having, respectively, a steam inlet and a steam outlet opening, and an intermediate diaphragm sheet, said sheets being secured together peripherally, and thimbles secured to the diaphragm sheet and one of the casing sheets, of return bend superheater pipes communicating with, and bearing at one end on the thimbles and communicating at the other 100 with openings in the casing sheet to which said thimbles are secured, on the edges of which openings they bear, yokes bearing on collars on said superheater pipes, and having openings through which said pipes pass with freedom of adjustment, and bolts securing said yokes to the connection casing.

7. In a steam boiler superheater, the combination, with a connection casing substantially as herein set forth, of return bend superheater pipes communicating at their ends with the chambers of the casing, yokes bearing on collars on said superheater pipes, thimbles extending through the connection casing and secured in the sheets thereof, bolts passing through said thimbles and through said yokes, and nuts engaging threads on said bolts and clamping the superheater pipes to seats on the connection casing.

8. In a steam boiler superheater, the combination, with a connection casing substantially as herein set forth, of return bend superheater pipes communicating at their ends with the chambers of the casing, yokes bearing on collars on said superheater pipes, thimbles extending through the connection casing and secured in the sheets thereof, bolts passing through said thimbles and through said yokes, nuts engaging said bolts and clamping the superheater pipes to seats on 130

- the connection casing, and spherical faced washers interposed between said bolts and said thimbles.
9. In a steam boiler superheater, the combination, with a connection casing substantially as herein set forth, of return bend superheater pipes communicating at their ends with the chambers of the casing, yokes bearing on collars on said superheater pipes, bolts passing through the connection casing and through said yokes, nuts engaging said bolts and clamping the superheater pipes to seats on the connection casing, and diametrically divided collets interposed between 10 the yokes and the collars of the superheating pipes.
10. In a steam boiler superheater, the combination, with a connection casing, substantially as herein set forth, of a breeching pipe having forked end portions registering with steam inlets in one chamber of the casing, branch delivery steam pipes registering with 15 the yokes and the collars of the superheating pipes.
11. In a steam boiler superheater connection casing, the combination of two wrought metal casing sheets, one at least of which is dished or pressed into channel form in 20 transverse section, and an intermediate diaphragm sheet, said casing and diaphragm sheets being secured together on their edges and forming a two chambered shell or casing which is centrally recessed at front to 25 clear a smoke stack, and is provided with two steam inlet openings on one of its sides, and two steam outlet openings on its opposite side, said openings being disposed in pairs on opposite sides of its front recess.

WILLIAM DALTON.
